No. 761,152.

PATENTED MAY 31, 1904.

W. J. DALY.

CLOCK CASE.

APPLICATION FILED JUNE 11, 1903.

NO MODEL.

UNITED STATES PATENT OFFICE.

WILLIAM J. DALY, OF BRISTOL, CONNECTICUT.

CLOCK-CASE.

SPECIFICATION forming part of Letters Patent No. 761,152, dated May 31, 1904.

Application filed June 11, 1903. Serial No. 161,044. (No model.)

To all whom it may concern:

Be it known that I, WILLIAM J. DALY, a citizen of the United States, residing at Bristol, in the county of Hartford, State of Connecticut, have invented certain new and useful Improvements in Clock-Cases, of which the following is a specification, reference being had therein to the accompanying drawings.

This invention relates to a clock-case, and particularly to a construction embodying a minimum weight of parts with a simplicity of construction which permits a very economical manufacture thereof.

The invention has for an object to provide a construction wherein the clock-movement may be supported by a depending cleat at the back of the case and a very light material used for said back, as no weight is carried thereby.

A further object of the invention is to provide an improved method of introducing and holding the glass portions of the case in position and also for connecting the base and cap of the case to the vertical posts comprising the angles thereof.

Other and further objects and advantages of the invention will be hereinafter set forth and the novel features thereof defined by the appended claims.

In the drawings, Figure 1 is a front elevation of the case. Fig. 2 is a central vertical section thereof. Fig. 3 is an end elevation with parts in section. Fig. 4 is a horizontal cross-section of the case. Fig. 5 is a detail elevation of a portion of the back thereof, and Fig. 6 is a detail plan of a portion of the body of the case.

Like letters of reference refer to like parts in the several figures of the drawings.

The letter A designates the base of the case, which may be of any desired construction or configuration, preferably provided with a back part A' and carrying upon a portion thereof a level A'', and at the top of the case a cap-section B is provided and ornamented in any desired manner—for instance, as herein illustrated—which section as formed is the heaviest part of the case and has secured thereto a hanger-plate B'. Depending from this cap B is a cleat or board B'', rigidly secured thereto

and adapted to support the clock-movement in proper position opposite the dial-opening. The base and cap are connected together at the front by means of vertical posts C, which are provided upon two of their faces with grooves C', adapted to receive the glass side panels C'' and the front panels C'', as shown in Fig. 4. The rear posts C'' are slotted, as at C'', and the glass panels just mentioned are passed through these slots and seated in the grooves C''. The lower ends of the side panels are held in position by means of a grooved block C'', while the upper end thereof is fitted into a similar block C''. As shown in the drawings, two side panels C'' are used, and the grooved blocks are duplicated at each side of the case. The rear posts C'' are secured to the cap B at their upper ends by means of screws C'', while the lower ends thereof are similarly secured to the base A by securing devices C''. The front posts C are secured to the cap B by means of screws D extending through a recess D' in the cap and entering the upper ends of the posts, while the lower ends of the posts are connected to the base by means of screws D'' entering the base and extending through a slot D'', by which the front panel of glass is introduced. The outer end of this screw passes through a plate D''' upon the under face of the base A. The glass panel just mentioned may be held in position by any desired means—for instance, the pivoted turn-button D'', adapted to swing across the under face of the slot D'' in the base.

For the purpose of forming the clock-case with a minimum of weight the usual heavy back is omitted, and the back panel E, of any suitable light material—for instance, cardboard—is secured to the rear posts C'' by means of screws E' or other suitable fastenings, these screws also forming the pivots for the turn-buttons E'', by which the side panels when introduced into the case are retained in position. The face of the case is provided adjacent to the dial-opening with a series of metallic sectors F, by which the circular opening is provided for the dial, these sectors being held in position by the upper portion of the groove C' in the front post C and by the grooved cross-bar F', extending between these front

posts and adapted to receive the sectors upon its upper face and the upper end of the panel C³ upon its under face, Fig. 1.

It will be seen that a clock-case constructed in accordance with this invention provides a case having a minimum of weight and one which can be readily assembled for use and taken apart for transportation, while the depending cleat from the cap of the case provides a rigid support directly connected to the wall-support for the case, by which the clock-movement is firmly held in position and against vibration. It will also be seen that the glass panels at the sides and the front of the clock are capable of convenient removal whenever necessary for repair or when it is desired to obtain access to the clock-movement from either side or the front thereof. It will thus be seen that the clock-case can be manufactured at a minimum of cost and presents a most efficient construction not requiring skilled workmanship.

It will be obvious that changes may be made in the details of construction and configuration without departing from the spirit of the invention as defined by the appended claims.

Having described my invention and set forth its merits, what I claim, and desire to secure by Letters Patent, is—

30 1. In a clock-case, a base, a cap, posts connecting said base and cap, a depending centrally-disposed cleat secured solely to the rear of said cap, a separate back panel secured to the rear posts of said case and independent of 35 said cleat, and means carried by the front posts for supporting a dial opposite said cleat.

2. In a clock-case, a base, a cap, parallel front posts connecting said base and cap and having grooved faces at an angle to each other, 40 parallel slotted rear posts in alinement with the front posts, a back panel carried by said rear posts, a removable front panel mounted in the opposite grooves in said front posts, side panels adapted to pass through the slotted rear posts and seat in grooves formed in the front posts, and means carried by the rear posts to prevent removal of said panels.

45 3. In a clock-case, a longitudinally-slotted base, a cap, connecting front posts extending between the base and cap, and having grooved faces in alinement with the ends of the slot in the base, slotted rear posts in alinement with the front posts, an independent back panel at the rear of said case, a removable

front panel adapted for introduction through 55 the slotted base into the grooves in the front posts, means carried by the under face of the base for securing said panel against removal, side panels adapted to pass through the slotted rear posts and seat in the grooves upon 60 the rear faces of the front posts, and means carried by the rear posts to prevent removal of said side panels.

4. In a clock-case, a slotted base, a cap therefor, connecting-posts extending between the 65 base and the cap, the front posts being grooved and the rear posts slotted, a depending cleat from said cap, a separate back panel at the rear of said case, removable front and side panels adapted to pass through the slotted rear posts 70 and seat in grooves formed in the front posts of the case, means carried by the rear posts and the base of the case to prevent removal of said panels, securing-screws extending through the cap and base and entering the 75 opposite ends of each front post, a grooved cross-bar extending between said front posts in alinement with the slot in the base, and segmental sectors seated in grooves in said posts and upper face of the cross-bar to form a dial- 80 opening.

5. In a clock-case, a base having a slot at its front portion, a cap, slotted rear posts connecting said cap and base and secured thereto, front posts provided with grooves at right 85 angles to each other and secured to the said cap and base, a front panel adapted to enter one of the grooves in said front posts, a turn-button upon the base to hold said panel in place, side panels adapted to pass through the 90 rear posts and enter grooves in said front posts, a back panel secured to said rear posts, turn-buttons provided upon said back panel for retaining said side panels in position, a depending cleat from said cap, a grooved cross- 95 bar extending between the front posts to receive the upper end of the front panel, a sectional dial-frame secured by grooves in the front posts and the upper face of said cross-bar, and a hanger secured to said depending 100 cleat.

In testimony whereof I affix my signature in presence of two witnesses.

WILLIAM J. DALY.
